UNITED STATES PATENT OFFICE.

ERNEST G. FRIEDRICH, OF INDIANAPOLIS, INDIANA.

SANITARY TOILET.

1,346,311.

Specification of Letters Patent. Patented July 13, 1920.

Application filed March 31, 1919. Serial No. 286,504.

To all whom it may concern:

Be it known that I, ERNEST G. FRIEDRICH, a citizen of the United States, and a resident of the city of Indianapolis, county of Marion, and State of Indiana, have invented certain new and useful Improvements in Sanitary Toilets, of which the following is a specification.

My invention relates to improvements in 10 toilet seats and seat covers in general and more particularly to means for washing and cleansing such seats after usage.

The principal object of my invention is 15 the construction of a toilet seat that will be washed and wiped after each usage thereof. A further object is to provide a seat that will be washed and wiped while in an upright or vertical position. A further object is to provide a seat that will be automatically washed by a predetermined flow 20 of water whenever the seat is raised or closed and which must be wiped before seat can be released for further usage. A further object is to provide a seat controlling 25 mechanism that may be readily adapted for operation by a coin-in-the-slot mechanism. A further object is to provide a mechanism that shall be automatic in action for closing and washing and manually operated 30 for release and which shall also be simple and inexpensive of construction and adapted to application on standard toilet fixtures.

With these objects in view, and such others as may appear, my invention relates 35 to details of mechanism and construction illustrated in a preferred form in the annexed drawings, it being understood that such modification thereof may be made as shall come within the spirit of the appended 40 claims.

In the drawings Figure 1 is a front view of the device with seat in closed position. Fig. 2 is a plan view. Fig. 3 is a vertical side elevation. Fig. 4 is an enlarged view 45 of the coin controlling mechanism, Fig. 5 being a side elevation of said mechanism, and Fig. 6 a sectional plan view of the coin slot. Fig. 7 is an enlarged fragmentary sectional view on line 6-6 of Fig. 1. Fig. 50 8 is a partial front elevation of an alternative construction of the wiper mechanism, Fig. 9 being a sectional plan view of the water controlling valve in closed position, and Fig. 10 a sectional plan of valve in 55 open position.

Referring more particularly to the drawings wherein like numbers refer to like parts throughout, the numeral 10 indicates a toilet bowl of any conventional design to the rear portion 11 of which a vertical cover 60 or housing 13 is fixedly attached as by bolts 12. The cover 13 is of box-like construction having a front cover or face 14 through which an arcuate recess 15 is formed for the reception of the seat 16. The seat 16 is 65 preferably cut away at its inner portion as at 18, leaving a connecting section or neck 17 to support the middle portion of cover 14, the seat being hingedly connected as at 19 to the supporting extension 20 of cover 70 13. Seat 16 may be provided with an inner and outer flange or rib 21-21' to assist in sealing the opening 15 against the leakage of water therethrough.

Centrally located in cover 13 is a stud 22 75 which may be provided with a reinforced bearing 23 carrying a projecting pin 24 to engage one end of a helical spring 25, the opposite end of said spring being connected to a pin 28 on a sleeve 27 surrounding a 80 portion of the stud 22. Fixedly attached to sleeve 27 is a flexible element 29 adapted to be wrapped or wound on said sleeve as at 26, the opposite end of said flexible element being attached for wrapping engagement upon a roller 37 attached to shaft 36 rotatably mounted within an extended housing or coin box 34 attached to the upper portion of cover 13. Fixedly mounted on sleeve 27 is a wiping arm 30 carrying a 85 wiping element 31 of any suitable flexible material, the outer extremity of arm 30 being carried and guided in a slot 32 formed in the periphery of cover 13. Arm 30 may be backwardly extended as at 30' in order 90 to give a double wiping contact on the face of the seat.

Fixedly attached to shaft 36 is an arm 35 carrying a handle or finger grip 39 projecting through an arcuate slot 38 in one 100 face of the housing 34. Pivotally mounted on arm 35 as at 41 is a pawl 40 riding through an arcuate housing 42 fixedly mounted on a partition 47 within said housing 34. Communicating with the arcuate 105 housing 42 is a coin receiving opening 43 and a spurious coin or slug discharging duct 44 communicating with an opening 45 through one wall of said housing 34, acceptable coins being discharged from housing 110

42 at its extremity 46. The free end of pawl 40 is arcuately adapted to the circumference of a coin 48. An opening 49 having a reduced portion 50 is formed in the 5 lower edge of housing 42 through which coins or slugs of smaller diameter or less thickness than the prescribed coin will pass and be ejected through opening 49, while an acceptable coin will rest in the arcuate 10 end of pawl 40 and will support said pawl during its passage over the enlarged portion 49 of said slot. If an attempt is made to operate the device without a suitable coin, the point 52 of pawl 40 will drop by gravity 15 into the enlarged opening 49 and engage the extremity 51 of said opening and prevent further movement of the arm 35 that operates the flexible element 29.

As an alternative construction to the roller 20 37 the extremity of flexible element 29 may be connected to an inwardly projecting pin 58 of arm 35, an idler pulley 59 being attached to housing 34 for directional guiding of said element 29. Also as an alternative 25 construction to the wiping element 31 arm 30 may be provided with an electrically heatable coil or element 53 connected by a wire 54 to any outside source of electric current, as at 55, an arcuate contact shoe 56 30 being slidably engageable with said coil, said shoe being electrically connected as at 57 to the opposite side of said electric circuit, contact between the element 53 and shoe 56 being broken when arm 30 is in retracted or inoperative position.

The seat 16 is raised from its horizontal position 16' to its closed position within the cover 13 by any suitable means, as a spring 65 or counterweight (not shown), and is retained in closed position by a pawl 62 engaging a notch or recess 63 in the outer periphery of said seat, said pawl being pivotally connected to a lever 60 pivotally connected as at 61 to the housing 34, a lug 64 45 being fixedly mounted on the flexible element 29 to engage with the lever 60 to release said seat by disengaging it from pawl 62.

Water is admitted within the cover through any suitable pipe 66 to which is attached a valve housing 68 with, preferably, 50 a conical seat 69 at one portion of its bore, the remaining portion 71 of the bore being straight. A valve plug 82 having a similar conical portion 70 and straight portion 72 is mounted within the bore of the valve, said plug having a central bore 74 and an annular chamber 81 for the reception of a helical spring 79. Within the bore 74 is loosely fitted a plunger 75 having an enlarged head 76, said plunger engaging a light helical spring 80 within said bore, a bypass 77 connecting said bore 74 with said inlet pipe 66 when said valve is closed. Water is discharged from said valve through an 60 outlet pipe 67 and may be distributed over 65

said toilet seat through any desired system of spray ducts or headers (not shown).

In operation the seat 16 is normally held in vertical closed position within the cover 13 by the spring 65. On the insertion of a 70 suitable coin within the coin slot the lever 35 may be arcuately moved carrying with it the flexible element 29 which causes rotation of the arm 30 and thoroughly wipes said seat by the wiping element 31 (or 53). 75 Strike 64 contacting with lever 60 operates the pawl 62 and releases the seat which may be lowered as desired. When the seat is released from a horizontal position it is again raised to a vertical position by spring 65 80 and contacts with the head 76 of plunger 75 which has been forced outwardly by spring 80. Plunger 75 closes the by-pass 77 and through the water imprisoned within the bore 74 the plug 82 is forced from its 85 seat and allows the free passage of water to the outlet pipe 67 from whence it is distributed over the seat. The water slowly escaping around the loosely fitted plunger 75 allows the gradual closing of the plug 90 82 under pressure of spring 79, thus stopping the flow of water to the discharge pipe 67. A suitable drain spout or sluice 33 may be provided to carry the water from the cover 13 into the body of the bowl 1. 95

Having thus described my invention, what I claim as new and desire to protect by these Letters Patent is:

1. In combination with a toilet bowl a housing rigidly fixed to said bowl, a seat 100 hingedly mounted on said housing, a stud centrally located within said housing, an arm rotatably mounted on said stud, a sleeve fixedly attached to said arm, a wiping element carried by said arm, a flexible element 105 mounted on said sleeve for rotation of said arm, means for operating said flexible element, means for ejecting water upon said seat when in said vertical closed position and means for carrying said ejected water from said housing to said bowl, substantially as described.

2. In a sanitary toilet a fixed vertical housing connected to a bowl, a seat receiving recess in one wall of said housing, a seat hingedly mounted upon said housing, spring actuated means for raising said seat from a horizontal to a vertical position within said recess, a lock for retaining said seat in said raised position, a wiper arm mounted for rotation within said housing, a wiper element contacting with said seat when carried by said arm, a flexible element for rotating said arm, coin controlled means for actuating said flexible element, means carried by said flexible element for releasing said seat restraining lock, a water controlling valve within said housing, means for actuating said valve by the closing of said seat, means for closing said valve after an 110 115 120 125 130

interval of time and means for spraying said water upon said seat and ejecting said water into said bowl, substantially as described.

3. In a sanitary toilet an upright housing, 5 a recess within said housing, a hingedly mounted seat closing said recess when in raised position, a rotary wiping element manually operated from without said housing, electric means for heating said wiping element, a valve within said housing, means for opening said valve with the closing of said seat, means for closing said valve after

an interval of time, means for distributing water from said valve upon said seat and for returning said water to said first mentioned bowl, substantially as and for the purpose described. 15

In testimony whereof I have signed my name to this specification in the presence of two subscribing witnesses.

ERNEST G. FRIEDRICH.
